UNITED STATES PATENT OFFICE.

ERNEST E. PETERSON, OF SOUTH HIBBING, MINNESOTA.

RAIL-CLAMPING MECHANISM FOR RAILWAY CARS.

Application filed August 20, 1928. Serial No. 300,619.

This invention relates to improvements in means for securing a railway car to the rails. It is particularly, although not exclusively, adapted for use upon track shifting machines of the type described in United States Patents Nos. 1,264,376 and 1,592,153, dated respectively April 30th, 1916 and July 13th, 1926. In such machines the car is provided with means for securing it to the rails and 10 with power driven mechanism for bodily raising and shifting the car, rails and ties laterally while elevated.

Heretofore it has been common practice to provide manually operable clamps for securing the cars to the rails and in all the old machines known to me the clamps are difficult and slow to operate and so constructed that they cannot be forced downward into engagement with the rails against obstructions such 15 as earth, ice or snow which often lodge upon the rails. This last mentioned defect has made it necessary, when shifting track with a machine of the old type, to have a workman go ahead of the machine and remove obstructing substances from the web and flanges of 20 the rails beneath the tread where the clamps engage. With the common track shifting machines an extra man must be employed for this work.

30 It is the object of my invention to obviate the work of cleaning the rails and to generally speed up the operation of machines of this type by providing power driven clamps adapted to automatically remove obstructing 35 matter from the rails. Other objects will appear and be more fully pointed out hereinafter.

The invention will be best understood by reference to the accompanying drawings in 40 which Figure 1 is a side elevation of my improved clamping mechanism mounted upon a railway car; Fig. 2 is a transverse section through the car and clamping mechanism taken on the line 2—2 of Fig. 1; Fig. 3 is a 45 fragmentary vertical section through the clamp operating mechanism taken on the line 3—3 of Fig. 2; Fig. 4 is a fragmentary front elevation of the automatic throw-out and adjacent mechanism of the clutch; Fig. 5 is a 50 plan view of the clutch mechanism; Fig. 6 is a fragmentary side elevation of a portion of the car and clamping mechanism and an alternate form of power driven clamp operating means; Fig. 7 is a horizontal section taken on 55 the line 7—7 of Fig. 1 and Fig. 8 is a longi-

tudinal section through the upper part of one of the clamp carriers.

My invention is shown mounted upon a suitable car 10 having the usual flanged wheels 11 adapted to run upon a pair of rails 12 of common type. The rails 12 are held in spaced, parallel relation by ties 13. Upon the car 10 is mounted a motor or engine 14 and suitable mechanism driven by the motor for operating a spud 15. This spud has a shoe 16 adapted to engage the road bed for elevating the car, rails and ties and for shifting the same laterally while elevated. As the details of the spud and operating mechanism form no part of the present invention, such mechanism is not fully described or illustrated herein. Suitable track shifting devices are described and claimed in the United States patents above identified.

In one form of my invention I utilize an 75 internal combustion engine 14 to quickly and positively actuate pairs of clamping jaws 17. To this end a sprocket wheel 18 is mounted upon the crank shaft 19 of the engine 14 and a parallel shaft 20 near the opposite end 80 of the car is arranged to be driven by a sprocket 21 on the latter shaft and a chain 22 connecting sprocket wheels 18 and 21. As best shown in Fig. 2 the shaft 20 is supported at its ends in suitable brackets 23 which are 85 bolted to the longitudinal frame members 24 of the car. Keyed to the shaft 20 so as to rotate therewith, but slideable longitudinally thereon, are clutch members 25 and 26 with friction contact faces 27 of conical form 90 (Figs. 2 and 5). The contact faces 27 of the clutch members 25 and 26 are adapted to engage conical recesses in clutch members 28 and 29, revolvable upon the shaft 20. Secured upon the adjacent faces of the members 28 95 and 29 is a pair of beveled gears 30 both of which mesh with a beveled gear 31 which is fixed upon a substantially vertical shaft 32 (Fig. 3). Bearings 33 are provided for the shaft 32 and these bearings are supported in 100 an auxiliary frame 34. To retain the shafts 20 and 32 in the same plane and to maintain the operative connection between the gears 30 and 31, a sleeve 20^a is mounted on the shaft 20 between the gears 30 and a stud 20^b projects 105 downward from the sleeve 20^a into an axial recess in the gear 31. The shaft 20 is revolvable in the sleeve 20^a and the gear 30 is freely revolvable about the stud 20^b.

A worm 35 fixed on the shaft 32 is arranged 110

to operate an arcuate gear 36 keyed to a horizontal shaft 37. The latter shaft extends across the car and has bearings in the frame members 24 and 34. Fixed upon the 5 shaft 37 near each end is a crank 38 having a forwardly projecting arm 39 arranged to impart longitudinal reciprocating movement to a rod 40 for operating one end of a clamp carriage. The clamp carriage consists of a 10 channel member 41 which is rigidly connected at each end by downwardly projecting arms 42 with a pair of supporting shafts 43 for the clamp jaws 17. Guides 44 for the channel members 41 are arranged to engage the sides 15 of said members and are provided with transverse stops 45 (Fig. 2) for downward movement of the clamp carriage. Between the vertical flanges on each of the channel members 41 is mounted a plate spring 46, the central portion of which is connected, as best shown in Fig. 8, to the member 41. The ends of the springs 46 normally project obliquely upward in spaced relation to the bottom of the channel members 41. Each end of each 20 spring 46 is perforated to receive one of the rods 40 and stops 47 are fixed on the latter rods to abut against the upper surfaces of the springs 46. At its lower end each of the rods 40 is bent laterally and inserted through 25 perforations in the adjacent ends of a pair of toggle members 48. The outer ends of the toggle members 48 are pivotally connected to upwardly projecting crank arms 49 severally fixed on the shafts 43. The clamping 30 jaws 17 are rigidly secured upon the shafts 43 so that oscillation of the shafts in the arms 42 operates the clamps.

As best shown in Figs. 1, 2 and 6, each 35 of the cranks 38 are provided, in addition to the forwardly projecting arms 39, with a downwardly projecting arm 50 connected by a link 51 to a similar downwardly projecting arm 52. As shown in Fig. 1 each arm 52 is pivoted upon a shaft 53 and integral with 40 another arm 54 arranged to impart reciprocating movement to the clamp operating rod 40 at the forward end of the clamp carriage. It will now be understood that two 45 pairs of clamping jaws 17 are provided to engage each rail and that the mechanisms for operating the clamps at the respective sides 50 of the car are similar.

To permit manual control of the operation of the power driven clamps, a clutch lever 55 is provided. This lever has a pivot 56 upon a transverse member 57 of the auxiliary frame 34 and projects above the floor of the car. Pivotally connected to the lever 55 above the member 57 is a clutch shifting bar 58, best shown in Figs. 3, 4 and 5. Slid- 55 able horizontally between the member 57 and a member 60 of the auxiliary frame, the bar 58 is connected by a pivot 61 with the lever 55 and formed at both ends with forks 62 60 respectively engaging annular recesses in the

clutch members 25 and 26. Secured in flanges 63 formed on the frame 34 and extending parallel to the shaft 20 is a guide rod 64. This guide rod passes freely through perforations in the forks 62 and extends axially through a pair of coiled springs 65 which are confined between the flanges 63 and forks 62. These springs 65 normally maintain both of the sliding clutch members 25 and 26 out of engagement with the clutch members 28 and 29. 70 75

To permit the retention of either of the clutch members 25 or 26 in driving engagement with the companion clutch member, means are provided on the lever 55 for selectively retaining it in positions corresponding to a notch 66 in the member 60 at one side of the neutral position, or to a notch 67 at the opposite side. The retaining means comprise a detent 68 of any suitable or well known construction adapted to be operated by a small lever 69 (Fig. 1) upon the grip of the lever 55. The lever 69 is operatively connected by suitable linkage 70 with the detent 68. 80 85

A throw-out is provided for the detent 68 whereby the clutch is freed to take its neutral position automatically when the clamping jaws 17 reach either extremity of their movement. This throw-out mechanism comprises a rocking member 71 pivoted at 72 on the frame member 60 and arranged to engage the detent 68 and raise it out of the notches 66 and 67. The rocking member 71 is pivotally connected at one side of its pivot with the upper end of an operating bar 73 which is slidably vertically in a suitable guide 74 upon the frame 34. The lower end of the bar 73 is provided with a laterally projecting finger 75 extending into the path of lugs 76 and 77 secured to a face of the gear 36. By this arrangement the lug 77 is caused to raise the bar 73 and operate the rocking member 71 to throw the detent 68 out of the notch 66 when the arcuate gear 36 has been turned 100 to one extremity of its movement. When the gear 36 reaches the other extremity of its movement the lug 76 strikes the finger 75 and draws the bar 73 downward to thereby disengage the detent 68 from the notch 67. In 105 either case, when the lever 55 is released it is moved, together with the clutch members 25 and 26, to neutral position by the action of the springs 65 against one of the forks 62. 110

In the alternate form of my device shown 115 in Fig. 6 a cylinder 78 is provided with a piston 81 and suitable pipe connections 79 and 80 at opposite ends for admitting a suitable operating fluid under pressure. A piston rod 82 projects from one end of the cylinder 78 120 and is connected with a lever 83 secured at its lower end upon the shaft 37. The clamp carriage, clamping jaws and connections of the same with the shaft 37 in the alternate form 125 are shown as identical with the correspond- 130

ing parts above described in connection with the preferred embodiment.

Operation.

- 5 In the illustration of the preferred embodiment, I have indicated an internal combustion engine 14 as a suitable form of motive power. Where such a motor is employed it may be continuously operated to rotate the 10 shaft 20 through the sprocket wheels 18 and 21 and chain 22. Assuming that the clamping jaws and clamp carriage are in elevated position (indicated in Fig. 6) where the jaws are out of engagement with the rails and that 15 the clutch lever 55 is in vertical or neutral position, the clutch members 25 and 26, keyed to the shaft 21, are both out of engagement with their companion clutch members 28 and 29 respectively. The clamp operating gears 20 30 and 31 are now stationary. To secure the car upon the rails the clutch lever 55 is moved so that its detent 68 engages in the notch 67. This slides the bar 58 to the right, as seen in Figs. 4 and 5, and causes the clutch member 25 to engage its companion member 28 which thereafter is rotated together with the gear 30. The gear 30 drives the gear 31 and shaft 32 carrying the worm 35 in mesh with the arcuate gear 36. Thus the gear 36 is slowly 25 turned in a clockwise direction from the position shown in Fig. 3 so that the shaft 37 is pivoted together with the crank 38 carrying the arms 39 and 50. Each of the arms 39, through its connection with the rod 40 at one 30 end of a clamp carriage, causes said end to be forced downward while an arm 50 through the link 51 and cranks 52 and 54 depresses the rod 40 at the opposite end of the clamp carriage to an equal extent. Thus the clamp 35 carriages at both sides of the car are moved downward between the guides 44. This movement of the clamp carriages continues until the channel bars 41 strike the stops 45 across the lower ends of the guides 44. During 40 the downward movement of the carriages the clamping jaws 17 remain in open position because there is substantially no relative movement of the pivot shafts 43 and the rods 40, motion being transmitted to the carriage 45 by the stiff plate springs 46. However, when downward movement of the channel bars 41 is arrested by the stops 45 tilting movement of the arms 39 and 54 continues against the action of the springs 46 so that all four of the 50 rods 40 are depressed relative to the pivot shafts 43. This causes the toggle members 48 to move the clamping jaws 17 to closed position by pivoting the shafts 43 having the cranks 49.
- 60 As the springs 46 approach their completely depressed position against the bottom of the channel members 41, the lug 76 upon the arcuate gear 36 strikes the finger 75 upon the bar 73 and draws said bar downward. 65 This, through the rocking member 71, throws
- the detent 68 out of the notch 67 so that the springs 65 are free to return the lever 55 and clutch members 25 and 26 to neutral position. Movement of the clamping jaws 17 is thus stopped when they reach their completely 70 closed position and the jaws remain closed by reason of the non-reversible connection between the worm 35 and arcuate gear 36.
- When it is desired to remove the clamp connection between the car and rails, the lever 75 55 is merely thrown to a position where the detent 68 engages the notch 66. This, by reason of the connection between the bar 58 and clutch member 26, causes the gear 31 to be driven in a direction such that rotation of 80 the worm 35 is reversed and causes the gear 36 to turn in a counter clockwise direction. The operation of clamping above described is thus reversed so that the clamping jaws 17 are first withdrawn from engagement with 85 the rail treads under the action of the springs 46 and are then raised together with the clamp carriages. As the clamp carriages approach the upper extremity of their movement between the guides 44 the lug 77 upon the gear 36 strikes the finger 75 and raises the bar 73 to disengage the detent 68 from the notch 66. The clutch members 25 and 26 under the action of the springs 65 are thus 90 returned to neutral position and rotation of 95 the worm 35 ceases.
- The operation of the alternate form of my invention, shown in Fig. 6, will be readily understood. When it is desired to lower the 100 clamping jaws 17 into engagement with the rails, air or other suitable fluid under pressure is admitted to the cylinder 78 through the pipe 80. This rocks the shaft 37 through the lever 83 and causes the clamps to be forced downward and then to be closed upon 105 the rails as above described in detail. Pressure is applied by the fluid in the pipe 80 to the piston 81 as long as the clamping action is desired. When it is desired to withdraw the clamps from the rails pressure in the 110 pipe 80 is released and fluid under pressure is admitted to the cylinder 78 through the pipe 79. This returns the mechanism to the position indicated in Fig. 6 where the clamp carriage is elevated free of the rails. 115
- It will now be understood that my invention may be used with different types of power actuating means and that the device may be employed wherever it is desirable to securely clamp a car upon the supporting 120 rails. The invention is not limited in its application to machines for shifting track.
- Having described my invention what I claim is new and desire to protect by Letters Patent is:
1. In rail clamping mechanism the combination with a rail and a car adapted to travel thereon, of a clamp carriage, positioned above said rail, guides for movement of said carriage toward and away from said rail, 125
- 130

clamping jaws arranged on said carriage to engage said rail, means adapted to positively move said carriage downward toward the rail and means for forcibly closing said jaws upon said rail.

2. In rail clamping mechanism the combination with a rail and a car adapted to travel thereon, of a clamp carriage positioned above said rail, guides for movement of said carriage toward and away from said rail, a plurality of pairs of clamping jaws arranged on said carriage to engage said rail, means for positively moving said carriage downward toward the rail and means for forcibly closing said jaws upon said rail.

3. In rail clamping mechanism the combination with a rail and car adapted to travel thereon, of a clamp carriage positioned above said rail and extending parallel thereto, guides for movement of said carriage toward and away from said rail, clamping jaws arranged on said carriage to engage said rail, power driven means adapted to move said carriage toward the rail and means for forcibly closing said jaws upon said rail.

4. The mechanism specified in claim 1 in which said carriage is provided with a pair of shafts extending parallel to the rail, said shafts constituting pivotal supports for said clamping jaws and crank arms fixed on said shafts for connecting said jaws to said closing means.

5. The mechanism specified in claim 1 in which said carriage comprises a pair of shafts extending parallel to the rail, said shafts constituting pivotal supports for said clamping jaws, a bar parallel with said shafts and rigid arms connecting said bar and shafts.

6. The mechanism specified in claim 1 in which a stop for downward movement of said carriage is provided, a member of said jaw closing means constituting a connection between the carriage moving means and carriage, and a spring interposed between said member and carriage whereby said jaws are retained in open position until downward movement of said carriage is arrested by said stop.

7. The mechanism specified in claim 2 in which a stop for downward movement of said carriage is provided, a member of said jaw closing means constituting a connection between the carriage moving means and carriage, and a spring interposed between said member and carriage for transmitting motion to said carriage and for retaining said jaws in open position until downward movement of said carriage is arrested by said stop.

8. In a device of the class described, the combination with a rail and car adapted to travel thereon, of a clamp carriage, guides

for movement of said carriage toward and away from said rail, rail clamping means arranged on said carriage to engage said rail, a member for actuating said clamping means to engage the rail, said member being connected to said carriage for moving the same toward and away from the rail and means for actuating said member to lower said carriage and to close said gripping means upon the rail.

9. In a device of the class described, the combination with a rail and car adapted to travel thereon, of a clamp carriage positioned above said rail, guides for movement of said carriage toward and away from said rail, rail clamping means arranged on said carriage to engage said rail, a member for actuating said clamping means to engage the rail, a spring connecting said member to said carriage for moving the same toward and away from the rail and means for actuating said member to lower said carriage and to close said gripping means upon the rail.

10. In rail clamping mechanism the combination with a rail and a car adapted to travel thereon, of a clamp carriage positioned above said rail, guides for movement of said carriage toward and away from said rail, a pair of clamping jaws arranged on said carriage to engage said rail, pivotal supports for said clamping jaws, toggle members operatively connected to said jaws, a rod for operating said toggle members, a connection between said rod and carriage for transmitting movement to said carriage and permitting relative movement between said rod and carriage and means connected to said rod for raising and lowering said carriage and for opening and closing said jaws.

11. In rail clamping mechanism the combination with a rail and a car adapted to travel thereon, of a clamp carriage positioned above said rail, guides for movement of said carriage toward and away from said rail, clamping jaws ranged on said carriage to engage said rail, an upwardly projecting rod for operating said jaws, a resilient connection between said rod and carriage for transmitting movement to said carriage and means connected to the upper end of said rod for raising and lowering said carriage and for opening and closing said jaws.

12. In rail clamping mechanism the combination with a rail and a car adapted to travel thereon, of a clamp carriage positioned above said rail, guides for movement of said carriage toward and away from said rail, a pair of clamping jaws arranged on said carriage to engage said rail, a pair of shafts extending parallel to said rail, said shafts constituting pivotal supports for said clamping jaws, a pair of crank arms for operating said jaws, toggle members operative-

ly connected to said cranks, an upwardly projecting rod for operating said toggle members, a resilient connection between said rod and carriage for transmitting movement to 5 said carriage and means connected to the upper end of said rod for raising and lowering said carriage and for opening and closing said jaws.

13. The mechanism specified in claim 1 in 10 which said means for moving the carriage downward include a power driven worm, a gear adapted to be turned by said worm and connections between said gear and clamp carriage.
14. The mechanism specified in claim 1 in 15 which said means for moving the carriage downward include a power driven worm, a gear adapted to be turned by said worm, a shaft adapted to be turned by said gear, connections between said shaft and carriage and 20

means for controlling the direction of rotation of said worm.

15. The mechanism specified in claim 1 in which said means for moving the carriage downward include a shaft, a worm on said 25 shaft, a gear adapted to be turned by said worm, a second shaft adapted to be turned by said gear, a connection between said second shaft and carriage and means for reversing the direction of rotation of said worm comprising a power driven shaft, a pair of 30 clutches associated with said power driven shaft, gears arranged to be selectively driven through said clutches, said gears being operatively connected to said first mentioned 35 shaft and manually operable control means for said clutches.

In testimony whereof, I have hereunto signed my name to this specification.

ERNEST E. PETERSON.
